UNITED STATES PATENT OFFICE.

JOHN SKUNDA, OF UREY, PENNSYLVANIA.

ICE-CREEPER.

1,144,155.

Specification of Letters Patent. Patented June 22, 1915.

Application filed April 20, 1915. Serial No. 22,566.

To all whom it may concern:

Be it known that I, JOHN SKUNDA, a citizen of the United States, residing at Urey, in the county of Indiana and State of Pennsylvania, have invented certain new and useful Improvements in Ice-Creepers, of which the following is a specification.

This invention relates to certain new and useful improvements in ice creepers.

10 The primary object of the invention is the provision of a creeper that is easy and cheap to manufacture but which may be readily clamped upon and removed from a shoe heel.

15 A further object is to provide a creeper plate removably secured to the tread portion of a shoe heel by binding cam operated clamping means, the same being readily releasable but locked in position when operatively positioned.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like designating characters refer to corresponding parts throughout the several views, Figure 1 is a side elevation of the device operatively positioned upon the heel of a shoe. Fig. 2 is a 35 front elevational view of the device. Fig. 3 is a top plan view thereof. Fig. 4 is a central sectional view taken through the forward portion of the device and the locking means therefor, and Fig. 5 is a perspective 40 view of the forward portion of the device with parts thereof removed.

Referring more in detail to the drawings, a shoe 10 is illustrated having the present invention operatively clamped upon the heel 45 11 thereof.

A tread plate 12 conforming substantially to the shape of the lower face of the shoe heel, is provided with pointed projecting calks 13, and has upwardly extending heel 50 engaging resilient side arms 14 and a rearwardly arranged co-operating arm 15 of slightly greater length. The said arms have inwardly-extending serrated flanges 16 forming teeth for engaging the adjacent side of 55 the shoe heel as best illustrated in Fig. 1. The forward side of the tread plate 12 has

a cruciform frame 17 mounted thereon and provided with oppositely positioned straps 18 upon its opposite arms 19.

An encircling metallic strap 20 is centrally secured as at 21 to the inner side of the rear arm 15 and adjacent the upper end thereof, and is forwardly bent in the substantial form of a shoe heel curve and has opposite longitudinal slots 22 therein which are slidably mounted upon inwardly-extending pins 23 of the side arms 14. The forward portions of the said strap 20 are angularly bent inwardly as at 24 and are slidably mounted through the said straps 18, their inner end 70 faces 25 being spaced apart and positioned upon opposite sides of a pivot pin 26.

An operating means is provided for connecting the adjacent strap ends composed of a segment cam 27 centrally pivoted upon the said pin 26 and having opposite cam slots 28 which slidably receive cam pins 29 therein which are mounted adjacent the free ends of the said strap 20 and upon opposite sides of the pin 26. The said segment cam 27 has an operating arm 30 extending therefrom, and the same is adapted to slidably engage a locking wedge 31 upon the outer side of the frame 17. With the arm 30 moved away from the said wedge 31, the segment cam will be shifted for releasing the strap 20 by separating the ends 25 thereof and in this position, the creeper may readily be positioned upon the heel with the strap surrounding the same and the teeth 16 arranged adjacent the side of the heel. A movement of the handle 30 to its locked position in engagement with the wedge 31 will then forcibly draw together the strap ends and the arms 14 and 15 being slightly resilient, the top toothed flanges thereof will be forcibly drawn into seating engagement with the shoe heel and the creeper will be thereby firmly locked upon the heel. The handle 30 will ride upwardly upon the wedge 31 and by its wedge action will be retained in engagement therewith in its locked operative position, while the handle may be readily swung out of engagement therewith for releasing the arm teeth and allowing the creeper to be removed from the heel.

While the form of the invention herein shown and described is what is believed to be the preferred embodiment thereof, it is nevertheless to be understood that minor changes may be made without departing

from the spirit and scope of the invention as claimed.

What I claim as new is:

1. A creeper comprising a calked tread plate, upwardly projecting side and rear heel engaging arms mounted thereon, a frame carried by the forward portion of the said plate, a positioning strap centrally secured to the said rear arm and slidably engaging said side arms and having its opposite ends inturned adjacent the said frame and connected thereto, and shiftable clamping means connecting the adjacent ends of the strap.
2. A creeper comprising a tread plate, heel engaging members projecting therefrom, a cruciform shaped frame mounted forwardly upon the said plate, a heel encircling strap connected with the said members and having its ends inturned and slidingly overlapping the side arms of the said frame, projecting pins upon the adjacent ends of the said strap, and an operating segment cam pivoted to the said frame intermediate

the ends of the said strap and having opposite cam slots therein shiftably seating over the said pins.

3. A creeper comprising a tread plate, heel engaging members projecting therefrom, a cruciform shaped frame mounted forwardly upon the said plate, a heel encircling strap connected with the said members and having its ends inturned and slidingly overlapping the side arms of the said frame, projecting pins upon the adjacent ends of the said strap, an operating segment cam pivoted to the said frame intermediate the ends of the said strap and having opposite cam slots therein shiftably seating over the said pins, a locking wedge carried by the said frame, an operating handle upon the said segment cam having a path of movement in the plane of the said wedge, straps carried by the said frame and positioningly surrounding the said strap ends, and ground engaging calks carried by the said plate.

In testimony whereof I affix my signature.

JOHN SKUNDA.
